FOUNTAIN PEN

Filed Feb. 4, 1937

INVENTOR.

Grand J. A. Ashley.

John D. and Frank M. ASHLEY, assignors to the United States Patent Office, and Lewis Gompers, trustee, New York, N. Y., have invented a new and useful improvement in fountain pens, and they desire to secure the patent rights in the United States and in other countries, and have therefore devised the following:

UNITED STATES PATENT OFFICE

2,124,280

FOUNTAIN PEN

Frank M. Ashley, Great Kills, N. Y., assignor to Lewis Gompers, trustee, New York, N. Y.

Application February 4, 1937, Serial No. 123,951

4 Claims. (Cl. 120—47)

My invention relates to fountain pens.

The object of my invention is to provide a pen construction of the self-filling type that will operate very freely in the act of filling the reservoir with ink.

5 A further object is to provide a pen that will hold a large volume of ink, and having means whereby a feed-chamber is provided which holds a quantity of ink such as can be controlled by the feed-plug, and a further quantity of ink that can be controlled by the piston which serves to separate the feed-chamber portion of the reservoir from the storage portion, and which may be easily operated to transfer ink from the main reservoir portion of the chamber to the feed portion thereof.

10 A further object is to provide a pen, the barrel of which may be made of transparent or translucent material to permit the ink therein to be viewed, and the interior of which is kept clear by the wiping action of the piston therein both in the filling operation, or by using water for the purpose.

15 Further objects of my invention and details of construction will now be described.

20 Referring to the drawing which forms a part of this specification:

Fig. 1 is a longitudinal sectional view of a pen embodying my invention, the valve being shown 25 in its closed position in

30 Fig. 2 in which the valve and piston is shown in section.

Fig. 3 is an end view of the piston, taken on line 3—3 of Figure 1.

35 Figure 4 is a longitudinal sectional view of a modified construction of the piston-valve.

40 10 indicates the barrel of the pen which may be made of transparent or translucent material, and 11 is the pen-section which is fitted in fluid-tight relation with the end of the barrel at 12.

45 13 indicates the feed-plug and 14 the pen proper.

15 indicates a central bore which extends from the inner end of the plug to near its front end, 50 and is intersected by a passage 15' located a predetermined distance from the end of the bore and having a smaller diameter than that of the bore.

16 indicates a small tube, preferably made of 55 hard rubber such as used for air-tubes in types of self-filling pens; said tube extending from the inner closed end of the bore and into the handle 17 of the piston-rod portion 16' of which said tube forms a part.

55 55 The tube portion 16' is provided with a stiff rod

18 one end of which extends into the central bore 19' formed in the piston 19 to strengthen the piston-rod at this point.

The piston 19 is mounted on the piston-rod in fixed relation, and is provided with one or more longitudinally extending passages 20, and with one or more passages 21 which extend from the rear side 23 of the piston and therethru to a passage 22 leading through the tube passage 24 in the tube.

25 indicates a valve which in Fig. 1, consists of a thin flexible disc of soft rubber which is held on the tube 16 by a ring 26 fixed thereon, and the diameter of the valve is less than that of the piston to permit ink to flow thru the piston passages 20 and over the outer edge of the valve when it is open, into the feed-chamber 27 from the reservoir chamber 28.

In Fig. 4, the piston is the same in construction as that shown in Figure 1, but the valve is a thin disc of hard rubber fitted to slide on the tube 16 and pressed against the face of the piston by a light spring pressure caused by a helical spring 29 which rests against the disc at one end and against a ring 30 mounted on the tube, at its other end; the valves being normally closed.

31 indicates the casing of a stuffing box and 31' the packing material therein which may be relatively a large mass to provide an elastic resilient cushion which closely fits the wall of the sliding piston-rod to maintain a fluid-tight joint without excessive friction, and the rod being of small diameter may be moved with a minimum of friction in the filling operation.

The casing 31 is provided with a thread 32 to receive the threaded end 33 of the handle 17, and the length of this thread is less than that of the distance between the passage 15' and the adjacent end of the tube 16, so that as long as the threads 32 engage the end 33 of the handle, the passage 15' will be closed by the end of the tube 16 overlying it.

45 The piston and valve may be located at any desired point on the piston-rod, depending on the relative size of the chambers desired.

The piston may be made of hard rubber and will slide in easy frictional relation with the wall of the barrel, the ink serving as a lubricant, and the reservoir will fill completely with two inward strokes of the piston after the front end of the pen-section has been immersed in ink.

50 When ink has been used from the feed-chamber and it is desired to add ink thereto from the reservoir chamber 28, the handle 17 is unscrewed nearly the length of the thread 32, which causes

ink to force the valve 25 to open and flow into the feed-chamber 27, and this action may be repeated until the desired amount of ink is transferred.

5 It will be noted that the end of the tube 16 has kept the passage 15' covered during this operation so that ink is not forced from the chamber 28 thru the tube during the outward stroke of the piston.

10 In filling the chambers with ink from a bottle, the outward stroke of the piston causes the fluid in chamber 28 to pass thru the tube 16 into the bottle, and thru the passages 20 into the feed-chamber, and on the inward strokes of the piston, 15 the valve 25 closes and ink is drawn from the bottle thru the tube 16 and fills the chamber 28 as fast as the piston travels; and on the second outward stroke of the piston, the ink flows more freely from the chamber 28 into the feed-chamber 20 than it does thru the tube 16, so that two or three strokes in each direction completely fills both chambers.

This construction provides positive means for forcing the ink from the main reservoir to the feed chamber, and for trapping the ink in the main reservoir; therefore the feed-plug can control the flow of ink in the feed-chamber without danger of flooding, even tho the pen as a whole is filled with much more ink than the feed-plug could control, were the main reservoir not closed and a large part of the ink had been removed therefrom, causing air to replace the ink used, which destroys the partial vacuum above the ink and permits the ink to flow from the reservoir, as will be readily understood.

35 In the present construction, the ink-duct 34 in the feed-plug is entirely separated from the bore 15.

The cap 35 is threaded in engagement with 40 the pen-section 13 at 36 instead of on the end of the barrel 10, which permits a smooth gripping surface on the barrel when the pen-section is made rather short, as will be readily understood.

Having thus described my invention I claim as new:

45 1. A fountain pen comprising a barrel, a feed-plug carried at one end thereof and provided with a central cylindrical bore which extends from its inner end to near its front end and having a passage leading from the atmosphere to said bore located at a predetermined distance from the closed end of said bore, a tube fitted to slide in close sliding relation in said bore, a connecting rod extending from the tube thru the rear end of said barrel, a piston movable by said connecting-rod and having a passage extending therethru, a valve controlling said passage, means for leading a liquid from the rear side of said piston thru said tube to the atmosphere, means for closing the rear end of said barrel, and a handle connected to said piston-rod.

50 2. The construction defined in claim 1, together with; and means for imparting a limited move-

ment of said piston-rod whereby the valve may be operated to force ink thru the passage in said piston from one side thereof to the opposite side without opening the passage leading thru the tube to the atmosphere.

5 3. A fountain pen comprising a barrel having a uniform cylindrical bore forming the reservoir therein, a feed-plug having a duct for ink, a pen overlying said duct; said feed-plug having a central bore extending from its rear end nearly to the forward end thereof and a passage for ink leading from the atmosphere to said bore and located a predetermined distance from the closed end of the bore, a tube fitted to slide in close contact with the wall of the bore and overlying the said passage for ink and extending from the bore into the reservoir, a piston carried by said tube, a piston-rod extending thru the rear end of said barrel, a piston actuated thereby having a passage leading therethru in open communication with said tube and also having a passage leading from one side thereof to the opposite side, a disc serving as a valve for said last named passage; said piston being located between the ends of said barrel to form two chambers in said barrel; the construction being such that the outward stroke of the piston opens said valve.

30 4. A fountain pen comprising a barrel, a pen-section carried in one end of said barrel, a feed-plug in said section having a feed-duct and a central bore separated therefrom and leading to the atmosphere thru a small passage located at a predetermined distance from the inner end of the bore, a tube fitted in said duct and extending 35 into the barrel, a piston directly connected to said tube, a piston-rod extending from the piston thru the rear end of the barrel, a stuffing-box for the piston-rod comprising a casing, said casing having a threaded end, a handle carried by the 40 piston-rod having a thread to engage the thread in casing and of less length than the length of the tube portion which extends beyond the small passage in the outer end of the feed-plug; said piston having a passage leading therethru to its 45 opposite side and a passage leading to said tube, a valve carried by the piston-rod adapted to close said passage leading thru the piston on the inward stroke thereof and open on the outward stroke, said valve being normally closed; said 50 piston being located between the opposite ends of the barrel to provide two chambers normally separated from each other but in open communication during the outward stroke of the piston; the construction being such that the piston may move in its outward direction a limited distance without opening the passage leading thru the tube to the atmosphere, and simultaneously causing the valve to open to permit a fluid in one 55 chamber to pass a quantity therefrom to the opposite chamber.

FRANK M. ASHLEY.
